FLUORESCENT LAMP SOCKET

Harvey Hubbell, Long Hill, and Joseph F. Healy, Jr., Bridgeport, Conn., assignors to Harvey Hubbell, Incorporated, Bridgeport, Conn., a corporation of Connecticut

Application December 22, 1939, Serial No. 310,600

12 Claims. (CL 173—328)

This invention relates to electric lamp sockets, particularly a socket for mounting fluorescent tubular lamps in which a pin type of mounting is used, that is, the external contacts are usually a pair of parallel pin type contacts projecting from the end of the tube. In this type of lamp the usual type of mounting requires a turning movement to the lamp in inserting it in and removing it from the socket, which on account of the limited space available is often difficult to accomplish. They are also often mounted in a suspended position and it is important that they be positively held in the socket and should not be accidentally released so as to permit the lamp to fall from the socket.

It is therefore an object of the present invention to provide an improved mounting socket for this type of lamp in which it may be inserted and removed by a straight or simple lateral movement, and in which it is locked in the socket, but with means for readily releasing the lamp to permit its removal from or mounting it in the socket, but that should it become accidentally released it will be held against dropping from the socket.

It is also an object to provide such a mounting socket which has incidental switch operation, or, in other words, in which the lamp may be partly released and this operation will open the circuit to the lamp.

Another object is to provide a construction in which the lamp is locked in the socket and released in two stages so that should one stage of the lock be accidentally released the lamp would still be retained in the socket because of the second stage.

With the foregoing and other objects in view we have devised a construction illustrated in the accompanying drawing forming a part of this specification. It will, however, be understood that we are not limited to the details shown but that various changes and modifications may be employed within the scope of the invention.

In this drawing:

Fig. 1 is a side elevation of a mounting showing how our improved socket may be employed in supporting tubular fluorescent lamps;

Fig. 2 is an elevation of the socket on an enlarged scale looking toward the outer side thereof with the cover plate removed and showing the lamp contacts in normal position;

Fig. 3 is a similar view showing one stage of the locking operation released and showing the position a suspended lamp occupies under these conditions;

Fig. 4 is a similar view showing the socket reversed so that the lamp is located above the support instead of being suspended from it;

Figs. 5 and 6 are a side and end elevation respectively of one end portion of a standard type of fluorescent lamp;

Fig. 7 is a side elevation of the inner spring contact in the socket;

Fig. 8 is an edge elevation of the outer spring contact; and

Fig. 9 is a view looking from the right of Fig. 8 with parts broken away to more clearly show the construction.

In Fig. 1 the fluorescent tubular lamp 10 is shown suspended by the sockets 11 from a base 12 of any suitable type or construction which ordinarily would be in any suitable type of enclosing casing, not shown, for good appearance and on which may be mounted the usual booster or control unit 13 properly connected by the wires 14 with the contacts in the sockets 11, and through them and the pin contacts 15 and 16 projecting from the ends of the lamp, with the electrodes in the lamp. These leads may be connected with a suitable attachment plug cap 17 for plugging into any suitable type of outlet or receptacle connected to the house wiring system.

The socket 11 is shown in detail in Figs. 2, 3 and 4. It comprises an insulating body 18 having a base 19 by which it may be mounted on the support 12. This body has in its inner side and extending from the end edge 20 thereof a slot 21 for insertion of the pin contacts 15, 16 by a lateral movement. The opposite side of the body is open and closed by an insulating plate 22 seated at its edges on the shoulders 23 and 24 surrounding the recess in the body and fastened thereto by any suitable means, such as screws 25.

The interior of the body is separated by division walls 26, 27 and 28 into chambers or compartments 29 and 30 in which are mounted spring contacts 31 and 32. The spring contact 31 is composed of a strip of resilient metal secured at its inner end to a plate 33 which is mounted in the body by seating at its edges in notches 34 and carries a binding screw 35 for connection to a lead wire 36. At its opposite end this contact 31 is curved backwardly upon itself at 37 and then curved laterally in the opposite direction to form a seat 38 extending across the slot 21 adjacent the inner end thereof. The other contact 32 is located in the chamber 30 and is secured at its inner end to a plate

39 similar to the plate 38 and mounted in the body by seating at its opposite edges in the recesses 40 in the opposing walls of the body. It also carries a binding screw 41 for connection of the other lead wire 42. Adjacent its other or outer end it is bent laterally to form a portion 43 extending across the slot 21, and also is preferably curved to form a seat 44 in alignment with the slot. On the opposite side of the slot it is bent backwardly and inclined outwardly as shown at 45. Secured to this contact adjacent its free end is a finger grip 46 which projects beyond the end edge 20 of the body in position to be easily accessible for operation to release the lamp in a manner presently to be described. It may be secured to the contact 32 by any suitable means, but in the present case the contact is shown as having laterally extending lugs 47 on one edge extending into openings in the member 46 which is preferably made of insulating material.

In Fig. 2 the parts are shown in the normal position with the lamp 18 in its normal operative position in the socket. In this position the inner pin contact 15 is seated in the seat 38 of the inner contact 31 while the outer pin contact 16 rests in the seat 44 in the other contact 32. The inclined cam portion 45 of this contact lies across the slot 21 at the inner side thereof and the pin contacts 15 and 16 are long enough to extend through the slot 21 and into the body or casing to engage the contacts 31 and 32. These contacts 15 and 16 are inserted into the socket by passing them through the outer or entrance end 48 of the slot 21. In doing this the pin 15 first engages the inclined portion 45, and as the lamp is forced inwardly, or upwardly as viewed in Fig. 2, the pin 15 has a camming action on the inclined portion 45 and forces this portion of the contact 32, as indicated in dotted lines Fig. 2, laterally to one side to permit the pin 15 to pass by the contact 32 into the slot 21 and later to engage the portion 38 of the contact 31. As the lamp is further forced inwardly, or upwardly as viewed in Fig. 2, the other pin contact 16 engages the inclined portion 45 and by camming action thereon forces it laterally as shown in dotted lines, the same as did the pin 15, to allow this pin 16 to pass through the slot 21 beyond the lateral portion 45 of the contact 32. As it does so the inner pin 15 engages the portion 38 of contact 31 and forces it inwardly or backwardly placing this spring contact 31 under tension. After pin 15 passes beyond this portion 45 the resiliency of the contact 32 brings it back to the full line position and the pin 15 rests in the seat 44. As the portion 38 of the spring contact 31 has been forced backwardly or inwardly this spring contact is placed under tension so that it presses on the pin 15 and tends to force the pin contacts 15 and 16 outwardly, or downwardly as viewed in Fig. 2, in the slot 21. This presses the pin 15 against the seat 44 of the contact 32 making good electrical contact between the socket contacts 31 and 32 and the lamp contacts 15 and 16. It will also be evident that the horizontal portion 43 and 44 of the contact 32, by holding the pin 15, retains the lamp contact pins in the socket.

If it is desired to remove the lamp from the socket all that is necessary is to press laterally on the projecting end of the finger piece 46 to shift it and the contact 32 laterally to the dotted line position of Fig. 2. This will move the portion 43 of contact 32 from its position across the

slot 21 and permit the contacts 15 and 16 to be removed, either by allowing them to drop out of the slot 21 or by lifting the lamp to carry them from the socket should the socket be mounted 5 in the reverse position with its free end edge 20 extending upwardly as shown in Fig. 4 instead of downwardly as shown in Fig. 2. It will be seen from the above that it is a simple operation either to mount the lamp with its contacts in the 10 socket or to remove it therefrom, and that the socket contacts 31 and 32 are separated and insulated from each other by the dividing walls 25 and 28.

With this device, however, should the projecting handle 46 be accidentally pushed to one side, as for example in handling or dusting about the device, it might be pushed aside sufficiently to release the contact portion 43 from the pin 15 and permit the lamp to drop under the action of 20 gravity or action of the spring contact 31, but as in these circumstances the finger piece 46 would be quickly released, contact 32 could spring back to its normal position, and although the outer contact pin 16 might have passed beyond the contact portion 45 the inner contact pin 15 would be caught by this portion 45 to prevent the lamp dropping entirely from the socket, as is shown in Fig. 3. If it is desired to entirely 25 remove the lamp from the socket all that is necessary is to again force the finger piece 46 and contact portion 43 to the right to release this pin 15.

It will thus be seen that the lamp contact pins are normally locked in the socket but under accidental operation are unlocked or released in 30 two stages, but for intended release of the lamp the contact 32 may be held back to permit easy removal of the lamp contacts. It will also be seen from Fig. 3 that when the outer contact pin 16 is released in the first stage to permit the lamp to drop to bring the contact 15 into the seat 44 of the contact 32 this permits the pin 15 to move away from and out of contact with the portion 38 of the contact 31, thus opening the circuit through the lamp, and if the lamp had been lighted its going out would indicate that the first stage of the locking means had been released. It also provides an incidental switch for extinguishing the lamp, as the user by merely releasing 35 this first stage to bring the lamp to the position of Fig. 3 can extinguish it, and can then relight it by pushing it upwardly or inwardly to the normal position. A shoulder 49 is provided in the body member to engage the end of the contact portion 38 as shown in Fig. 3 to limit downward movement of this contact, and thus insure that it does not remain in engagement with the pin 15 when the lamp is partly unlocked 40 as shown in Fig. 3.

The same effect and operation is secured when 45 the socket is reversed as shown in Fig. 4. Although in this position the lamp could not drop from the socket when it becomes unlocked, still if the finger piece 46 is accidentally or otherwise forced to one side to release the outer pin contact 16 the lamp and its contacts will be forced upwardly by spring action of the contact 31, and as after the outer pin 16 passes beyond the horizontal portion 43 of the contact 32 this contact 50 moves back to its normal position the outer pin contact 16, as shown in Fig. 4, will rest on top of the inclined cam portion 45 and will be retained in the position of Fig. 4 with the inner contact pin 15 supported above and away from the seat 38, and therefore out of engagement 55

with the contact 31. Thus the circuit through the lamp is broken and we secure the incidental switch action in this arrangement of the socket the same as we did with the socket arranged as in Figs. 2 and 3. We also have the locking and releasing of the contacts by two stages as in the first arrangement. It will further be evident that the socket can be used in the horizontal position if desired and will function in the same manner. Although contacts 31 and 32 are shown as resilient or spring contacts they could be rigid or flexible contacts mounted for lateral movement under action of separate springs.

It will be evident from the above that we have provided a simple socket for this type of lamp into which the lamp contacts may be inserted and from which they may be removed quickly and easily with simple sliding movements, but that the contacts are effectively held in the socket. Also that the two stage locking and unlocking feature greatly reduces the liability of the lamp being accidentally released from the socket, but permits quick and easy removal from the socket if desired. Further, this double release feature gives incidental switch operation.

Having thus set forth the nature of our invention, what we claim is:

1. In a socket support for lamps with a pair of spaced parallel pin contacts, said support including a body having a slot to receive both of said contacts by lateral movement in the plane of the contacts only, a pair of spaced spring contacts extending across said slot and each arranged when the lamp is in the socket to engage one pin contact on the side thereof opposite the other pin contact, and both spring contacts tending to move toward each other to press on the respective pin contacts to support the lamp.

2. In a socket support for lamps having a pair of spaced parallel pin contacts, an insulating body having a slot leading from one edge for insertion of both the said lamp contacts by a lateral movement in the plane of the contacts only, a pair of spring contacts carried by the body having seats for the respective pin contacts facing in opposite directions and extending transversely of the slot to retain the pin contacts in the said slot between the spring contacts, and one of the spring contacts being movable laterally to permit the pin contacts to move into and out of the slot by movements in the plane of the contacts only.

3. In a socket support for lamps having spaced parallel pin contacts, an insulating body having a slot leading from one edge for insertion of the lamp contacts by a lateral movement, a pair of spring contacts carried by the body respectively spaced inwardly different distances from the entrance to the slot and having seats for the respective pin contacts facing in opposite directions to retain the pin contacts, the outer spring contact being movable laterally to permit movement of the pin contacts into and from the slot, and said latter spring contact also having an inclined portion outwardly of the seat thereon toward the slot entrance for engagement by a pin contact as it is inserted in the slot to force said spring contact laterally.

4. In a socket support for lamps having spaced parallel pin contacts, an insulating body having a slot leading from one edge for insertion of the lamp contacts by a lateral movement, a pair of spaced spring contacts in the body respectively located inwardly different distances from the

slot entrance and forming spaced seats facing in opposite directions to receive the pin contacts, and said outer spring contact having an inclined cam surface outwardly of its seat toward the slot entrance for engagement by a pin contact as it moves inwardly in the slot to move said spring contact laterally to permit passage of the pin contacts to said seats.

5. In a socket support for lamps having spaced parallel pin contacts, an insulating body having a slot leading from one edge for insertion of the lamp contacts by a lateral movement in the plane of the contacts, a spring contact forming a seat to receive the inner pin contact and tending to force said pin contact outwardly toward the entrance to the slot, a second spring contact extending across the slot and forming a seat for the outer pin contact to retain it in the slot, and means for moving the second spring contact to one side to permit passage of the pin contacts in the slot.

6. In a socket support for lamps having spaced parallel pin contacts, an insulating body having a slot leading from one edge for insertion of the lamp contacts by a lateral movement in the plane of the contacts, a spring contact forming a seat to receive the inner pin contact and tending to force said pin contact outwardly through the slot, a second spring contact extending across the slot and forming a seat for the outer pin contact to retain it in the slot, and said second spring contact having an inclined portion outwardly of said seat to coact with the pin contacts as they move into the slot to shift said spring contact laterally to permit passage of the pin contacts.

7. In a socket support for lamps having spaced parallel pin contacts, an insulating body having a slot leading from one edge for insertion of the lamp contacts by a lateral movement in the plane of these contacts, a spring contact forming a seat to receive the inner pin contact when the pin contacts are inserted in the slot and tending to force said pin contact outwardly toward the slot entrance, a second spring contact extending across the slot and forming a seat for the outer pin contact to retain it in the slot, said second spring contact having an inclined cam surface outwardly of its seat to coact with the pin contacts as they move into the slot to shift the second spring contact laterally, a manually operable means to shift said second spring contact laterally to permit passage of the pin contacts, and said seat and cam surface on the second spring contact being so spaced from the first spring contact that when the outer pin contact is outwardly of the second spring contact the inner pin contact is separated from the first spring contact to open the circuit through the lamp.

8. In a socket support for lamps having spaced parallel pin contacts, an insulating body having a slot leading from one edge for insertion of the lamp contacts by a lateral movement, a first spring contact forming a seat to receive the inner pin contact and tending to force said pin contact outwardly toward the slot entrance, a second spring contact to engage the outer pin contact to retain the lamp in the socket, a manually operable means to shift the second spring contact laterally to permit passage of the outer pin contact under action of the first spring contact and to permit the inner pin to move away from the first spring contact, and means operable after such movement to retain the inner pin con-

tact in its new position out of contact with the first spring contact to open the circuit through the lamp.

9. In a socket support for lamps having spaced parallel pin contacts, an insulating body having a slot leading from one edge for insertion of both the lamp contacts by a lateral movement with one contact located inwardly from the other, a first spring contact forming a seat to receive the inner pin contact and tending to force said pin contact outwardly toward the slot entrance, a second spring contact engaging the outer pin contact to retain it in the slot and tending to move to this holding position, manual means to shift the second spring contact to permit outward movement of the outer pin contact, and said second spring contact having means to engage one of the pin contacts after such movement to support the lamp with the inner pin contact out of engagement with the first spring contact. 10

10. In a socket support for lamps having spaced parallel pin contacts, an insulating body having a slot to receive said contacts, a first spring contact in the body to engage one of the pin contacts and tend to force said pin contacts from the body, a second spring operated contact to engage the other pin contact and retain it in the body against the action of the first spring contact, and a manual means for shifting the second spring contact to permit passage of the 30 pin contacts from the body. 20

11. In a socket support for lamps having spaced parallel pin contacts, an insulating body having a slot to receive said contacts, a first spring contact in the body to engage one of the pin contacts and tend to force said pin contacts from the body, a second spring operated contact to engage the other pin contact and retain it in the body against the action of the first spring contact, a manual means for shifting the second spring contact to release the pin contacts to permit passage of these pin contacts from the body and permit the first mentioned pin contact to move away from the first spring contact, and means on the second spring contact to engage one of the pin contacts after release of the second pin contact to retain the first pin contact in its new position out of engagement with the first spring contact.

12. In a socket support for lamps having spaced parallel pin contacts, an insulating body, a pair of spring contacts in the body arranged to engage the respective pin contacts, one of the spring contacts tending to force the pins from the body and the other holding them against action of the first spring contact, manual means to operate the second spring contact to release the pins, and means operable after release of one of the pins to retain the other pin in the body.
